INVENTOR

W. E. Snaman,

UNITED STATES PATENT OFFICE.

WILLIAM E. SNAMAN, OF ALLEGHENY, PENNSYLVANIA.

DOOR FOR SIDEWALKS.

No. 894,754.

Specification of Letters Patent.

Patented July 28, 1908.

Application filed October 23, 1907. Serial No. 398,747.

To all whom it may concern:

Be it known that I, WILLIAM E. SNAMAN, a citizen of the United States of America, residing at Allegheny, in the county of Allegheny and State of Pennsylvania, have invented certain new and useful Improvements in Doors for Sidewalks, of which the following is a specification, reference being had therein to the accompanying drawing.

10 This invention relates to doors for sidewalks, and the invention has for its object to provide an air and water proof door that will lie flush with the surfaces of a pavement or sidewalk.

15 My invention aims to provide a simple and inexpensive door, which will avoid undue obstructions or raised surfaces in a sidewalk, said door being of a novel construction, wherein prevention is made against leakage 20 through crevices surrounding the door edges. In this connection, my improved door is particularly designed to be used as a scuttle door a man hole covering, a hatch way covering or a trap door, the door being constructed 25 whereby it may be made air tight, water proof and free from all danger of injury by ordinary use. To this end, I have constructed a novel door frame adapted to be located in a sidewalk or pavement, the frame 30 providing a gutter that can be easily drained or cleaned, thus preventing water, dirt and filth from interfering with the operation or seating of the door and from entering the chamber or passage way which the door normally closes. The door is constructed of 35 strong and durable metal and is provided with a novel hinge, which permits of the door lying flush with the surface of a sidewalk or pavement, the hinged side or sides of the 40 door being strengthened and protected within the sidewalk of stone, concrete or other material.

The detail construction entering into my invention will be hereinafter more fully described and then specifically pointed out in the appended claims.

Referring to the drawing forming part of this specification, like numerals of reference designate corresponding parts throughout 50 the several views, in which:

Figure 1 is a cross sectional view of a door frame constructed in accordance with my invention illustrating the doors thereof in end

view, Figs. 2 to 6 inclusive are detail sectional views of door frames, illustrating various modifications of my invention, Fig. 7 is a detail sectional view of a door frame illustrating a novel form of hinge wherein the door is supported slightly above a sidewalk, Fig. 8 is a similar view illustrating a door supported flush with a sidewalk, Fig. 9 is a detail sectional view of a portion of a sidewalk illustrating the manner of anchoring a hinge therein, Fig. 10 is a detail sectional view of two doors illustrating the manner in which an entire sidewalk can be constructed of hinged sections.

In the accompanying drawing, 1 indicates a hatch way or chamber located in the sidewalk 2, and countersunk in the sidewalk 2 is 70 a rectangular metallic frame 3 constructed of angle iron. Upon the frame 3 within the sidewalk 1 arrange a rectangular gutter 4 which is substantially channel-shaped in cross section, the inner sides 5 of said frames 75 being of a less depth than the outer sides thereof. The gutter 4 is provided with a suitable drain pipe 6 for removing water therefrom.

Suitably secured to the inner sides 5 of the 80 gutter are hinges 7, said hinges carrying doors 8 and 9 adapted to fall inwardly. The underneath sides of the doors 8 and 9 are provided with gaskets 10 of a resilient material such as rubber, said gaskets resting upon the 85 water proof connection. The meeting edge inner sides 5 of the frame 3 and providing a of the door 9 is provided with a depending channel-shaped metallic strip 11. The strip 11 is adapted to receive an angle iron 14 carried by the meeting edge of the door 8 and if desirable a resilient strip 15 can be located in the bottom of the channel-shaped strip 11 to provide a positive connection of the two 90 doors and cushion the door 8 in said strip. The ends of the doors 8 and 9 overlying the frame 3 will firmly support the meeting edges 95 of the doors, thereby dispensing with the ordinary bar commonly used for supporting the meeting edges. The novel manner in 100 which the meeting edges are connected together prevents the doors from sagging and getting out of alinement with the level of the pavement. The doors are rendered air tight by employing the gasket 10 and the resilient 105 strip 15, while the channel-shaped frame 3

and channel-shaped strip 10 prevents water from entering the passage way or chamber I which is normally closed by the doors 8 and 9.

It will be observed that the horizontal flange 16 of the frame 3 projects beyond the frame 4, thus more firmly anchoring the frame 3 in the side walk or pavement 2.

In Fig. 2 of the drawing, I have illustrated a slight modification of my invention wherein I have dispensed with the channel-shaped frame 4 and employed a frame constructed of angle bars 17, said bars having their horizontal flanges 18, protruding a sufficient distance into the side walk or pavement 2 to provide a firm anchorage. The sidewalk or pavement 2 is recessed as at 19, to clear the movement of the hinge 7. In this view, I still retain the frame 3, but as illustrated in the remaining figures of the drawing, namely Figs. 3 to 9 inclusive, I dispense with said frame.

Another modification of my invention is illustrated in Fig. 4 of the drawings, where I provide the doors with angle irons 20, having strips of resilient material 21 adapted to engage the angle bars 17, the strips of resilient material serving as weather strips.

In Fig. 5 of the drawing, I have illustrated another modification wherein the frame 22 of the passage way or compartment 1 extends within close proximity to the top of the sidewalk 2 and carries the hinges 7 for supporting the doors. The frame 22 is provided with ordinary Z-bars 23, to provide clearance 24 for the hinged doors. A slight modification of this construction is illustrated in Fig. 6 wherein the Z-bars are dispensed with and curved bars 25 used.

In Fig. 7 of the drawing, I have illustrated a passage way or chamber frame 26 having a horizontal flange 27, provided with a rib 28. Secured to the frame 26 is a hinge 29, the member 30 of said hinge being secured to one of the doors, and constructed to clear the flange 27, when the door is swung open. The hinged edge of the door is grooved, as at 31, to engage over the rib 28 when the door is closed, this form of frame and hinge supporting the door slightly above the level of the side walk or pavement 2.

In Fig. 8 of the drawing, I have illustrated practically the same hinge as applied to the frame 26, said frame having its horizontal flange 27 provided with a seat 32. In this connection, the door 8 is supported on a level flush with the surface of the sidewalk or pavement.

In the above mentioned Figs. 7 and 8, the hinged members 30 are employed for supporting metallic gutters 30^a, said gutters collecting water, dirt and such material that may enter the passage way or chamber of the pavement or sidewalk 2. In some instances, I may entirely dispense with the hinged mem-

bers 30 and use the metallic gutters 30^a in lieu thereof.

A still further modification of my invention is illustrated in Fig. 9 of the drawing, wherein the sidewalk or pavement 2 is provided with a hinge 33 having an anchorage 34 in the pavement or sidewalk, said pavement or sidewalk being recessed as at 35, to clear the movement of the hinged door 8. The pavement or sidewalk 2 is provided with a resilient strip of material 33^a, to provide an air tight and water proof connection between the pavement or sidewalk 2 and the doors 8 and 9. I attach considerable importance to this modification, owing to the fact that the frames are entirely dispensed with, the hinges being embedded within the concrete construction of the pavement or sidewalk.

In Fig. 10 of the drawing, is shown a construction adapted for sidewalks and pavements wherein hinged doors or sections 8 and 9 are provided with transparent plates or lights 36. The doors or sections 8 and 9 are hinged in a beam 37 of the channel construction.

Throughout the various constructions disclosed above it will be observed that I have devised novel doors that can be readily opened from the inside of a passage way or chamber, the doors and their supporting elements being particularly designed for concrete pavements and sidewalks.

While I have herein described the construction illustrated in Fig. 1 as the preferred form, it is obvious that I may use such forms as are permissible by the scope of the appended claims.

What I claim and desire to secure by Letters Patent, is:—

1. The combination with a sidewalk or pavement, having a passage way or chamber formed therein, of a metallic frame surrounding the edges of said passage way, a metallic channel-shaped frame supported upon said metallic frame and having its inner sides of less depth than its outer sides, doors hinged to the inner sides of said channel-shaped frame, gaskets carried by said doors and adapted to impinge the inner sides of said channel shaped frame, a channel-shaped strip carried by the meeting edge of one of said doors, an angle iron carried by the meeting edge of the other of said doors and adapted to enter said channel-shaped strip, and a drain pipe connecting with said channel-shaped frame.

2. In a door for sidewalks, the combination with a sidewalk having a doorway, of a door-securing member arranged in the sidewalk and constituting one wall of a gutter extending around the doorway, doors hinged to said door-securing member having their side edges overlying the door-securing member and covering the gutter at the sides of the

door way and their ends overlying and covering said gutter at the ends of the doorway, the said gutters affording clearance for the hinged side edges of the doors to permit the 5 raising of the latter.

3. In a door for sidewalks, the combination with a sidewalk having a doorway surrounded by a gutter or recess, of door-securing members arranged in the sidewalk with 10 respect to said gutter or recess as to constitute one wall thereof, and doors hinged to said members, the said doors being supported throughout the length of said door-securing members when the doors are in the closed 15 position, said members also acting to support the doors upright when the doors are in open position.

4. In a door for sidewalks, the combination with a sidewalk having a doorway surrounded by a gutter or recess, of a door-securing member arranged in the sidewalk with 20 respect to the gutter or recess as to constitute one wall thereof and form a continuous support for a door entirely around the doorway, and a door hinged to said door-securing member, the said door-securing member also 25 acting as a support for the door when the latter is in an open position.

5. In a door for sidewalks, the combination with a sidewalk having a doorway and a gutter or recess in the sidewalk outside the doorway, of a door-securing member arranged in the sidewalk with respect to the gutter or recess as to constitute one wall 30 thereof and form a continuous support throughout its length for a door, and a door hinged to said door-securing member, the point of hinging the door to the member being such that when the door is closed the hinged 35 edge of the same overlies and covers the gutter or recess and when the door is opened the gutter or recess affords clearance for the movement of said hinged edge and the said 40

wall of the member acts to support the door in the open position.

6. In a door for sidewalks, the combination with a sidewalk having a doorway surrounded by a gutter or recess, of a door-securing member arranged in the sidewalk with 45 respect to the gutter or recess as to constitute one wall thereof and form a continuous support entirely around the doorway for doors hinged thereto, doors hinged to said door-securing member, the point of hinging the doors to the member being such that when the doors are closed the hinged edges of the same overlie and cover the gutter or recess at opposite sides of the doorway and when the doors are opened the gutter or recess at 50 said opposite sides of the doorway affords clearance for the movement of said hinged edges, the said wall of the door-securing member also acting to support the doors when the latter are in an open position.

7. In a door for sidewalks, the combination with a sidewalk having a doorway surrounded by a gutter or recess, of a door-securing member arranged in the sidewalk with 55 respect to the gutter or recess as to provide a continuous support for the doors entirely 60 around the doorway, doors hinged to said door-securing member, the point of hinging the doors to the member being such that the hinged edges thereof overlie and cover the gutter or recess at opposite sides of the doorway, the said gutter or recess affording clearance for the movement of said hinged edges when the doors are opened, said door-securing member constituting a support for the doors when the latter are in open position. 65 70 75 80

In testimony whereof I affix my signature in the presence of two witnesses.

WILLIAM E. SNAMAN.
